UNITED STATES PATENT OFFICE

SYLVESTER W. CROWLEY, OF HILLSIDE, NEW JERSEY, ASSIGNOR TO DE FOREST RADIO COMPANY, OF PASSAIC, NEW JERSEY, A CORPORATION OF DELAWARE

ELECTRON DISCHARGE DEVICE

No Drawing. Original application filed March 1, 1924, Serial No. 696,396. Divided and this application filed March 14, 1930. Serial No. 435,970.

This invention relates to electron discharge devices and more particularly to the means by which the same are exhausted.

The objects of the invention are to enable 5 an electron discharge device to be manufactured in less time than heretofore; to reduce the time and expense involved in obtaining a high degree of evacuation of the device; to employ a chemical clean-up agency 10 for obtaining part of the evacuation; to employ a "flash" as well as a chemical clean-up agency; to employ a chemical clean-up agency and flash adapted to be applied simultaneously and put into effect at different times; to 15 enable the chemical clean-up agency and flash to be put into effect by use of high frequency or by plate bombardment; to obtain an improved method of manufacture; to secure simplicity of construction and operation, and 20 to obtain other advantages and results as may be brought out in the following description.

In the manufacture of electron discharge devices, it has become more or less common practice to employ a filament which includes 25 the element thorium as the emissive substance. Thorium oxidizes quite readily and consequently the filament as inserted in an electron discharge device contains exposed portions of thorium oxide rather than pure 30 thorium. In order to reduce thorium oxide to thorium, it has become common practice to employ a flash of some suitable material, of which magnesium is the one most generally used. The operation is ordinarily carried 35 out by applying a small portion of magnesium to the plate and then after the tube is evacuated as much as possible by the pump, the plate is heated to a point where the magnesium will flash and the resulting vapor will 40 operate to reduce the thorium oxide to thorium. The present invention contemplates means for first obtaining a partial vacuum by means of a pump, so as to materially reduce the time during which the electron dis- 45 charge device has to be connected with the pump for the purpose of evacuation, and then high evacuation is obtained by other means, after which the magnesium or other material may be flashed similar to the manner in 50 which that operation has been carried on

heretofore. In order to obtain the high vacuum by means other than pumping, I employ a chemical which is flashed similar to the magnesium, preferably before the magnesium is flashed, said chemical obtaining a high state of evacuation of the tube by means or reduction of the residual gases within the tube. The magnesium could not be used practically for this purpose, both because it is not sufficiently active to reduce the residual 55 gases to the necessary amount, nor is it practical to flash the magnesium until a very much higher degree of evacuation has been effected than is required in connection with the present invention. 60

I preferably employ in combination with a flash of magnesium or other suitable material, chemical clean-up agency of phosphorus. The advantage of employing phosphorus is that it may be flashed at a lower temperature 65 than magnesium and also that phosphorus will effectively reduce the residual gases when flashed while the device is not in such a high state of evacuation as necessary to obtain reduction by means of magnesium. I 70 may also state that very good results are obtained by use of red or amorphous phosphorus. Since phosphorus in this state is more convenient to handle and does not have to be protected until ready to be flashed, it 75 is the better variety to use.

In order to apply the phosphorus to the plate or other part from which it is to be flashed, I preferably mix the phosphorus and magnesium in the nature of a paste or paint 80 and apply it with a brush or in any other suitable manner. As much of the plate as desired may be covered with the mixture, although it will probably be sufficient in most cases to employ only a good size spot on the 85 plate. I do not wish it to be understood that it is necessary to mix the phosphorus and magnesium, and indeed, in some instances it may be highly desirable not to mix the two. 90

The flashing of the phosphorus and magnesium, as indicated above, takes place at different times, phosphorus being flashed first in order to reduce the residual gases and obtain a higher degree of evacuation, after 95 which the magnesium is flashed in order to 100

reduce the thorium oxide of the filament to thorium. There are a number of ways of obtaining the flash of the phosphorus and magnesium one instance of which is the usual method of plate bombardment. The temperature of the plate is raised by means of an initial electron emission to such a point as to cause the phosphorus to vaporize and combine with the residual gases. Continued bombardment of the plate will raise the temperature to a higher degree and thus obtain a subsequent flashing of the magnesium. The flashing of magnesium has heretofore been effected by means of high frequency current, and this may also be utilized for flashing the phosphorus. In order to obtain a marked time difference between the flashing of the phosphorus and magnesium, the phosphorus may be applied to the plate toward one end of the electron discharge device and the magnesium applied to the plate toward the other end, so that the high frequency coil may be manipulated to operate only on the end of the plate to which the phosphorus is applied, so as to flash the phosphorus and then moved along so as to operate upon the other end of the plate and flash the magnesium.

It is apparent that both the phosphorus and the magnesium provide clean-up agents both of which are flashed but at different temperatures. In the broad aspect of this invention any two suitable agents could be used which are adapted to be flashed at different temperatures. The term "flash" as used in the claims relates to the agent adapted to be activated at the higher temperature.

Obviously other detail changes and modifications may be made in the manufacture and use of my improved electron discharge device, and I do not wish to be understood as limiting myself to the exact structure or method described, except as set forth in the following claims when construed in the light of the prior art.

This case is a division of application Serial No. 696,396 filed March 1, 1924.

What is claimed is:

1. The method of manufacturing an electron discharge device having a thoriated filament which comprises applying a chemical clean-up agent and a filament flash material at different parts of said device, energizing the clean-up agency and subsequently energizing the flash material.

2. The method according to claim 1 in which the energization of the clean-up agent and the flash material is effected by high frequency currents.

3. The method of manufacturing electron discharge devices which comprises applying a chemical clean-up agent to one part of said device, applying a flash material at a different part of said device, subjecting said clean-up agent to the action of a high-frequency field, and moving said field to sub-

sequently subject said flash material thereto.

4. An electron discharge device of the type having a thoriated filament, a chemical clean-up agent applied to one portion of said device, and a filament flash material of magnesium applied to a different portion of said device.

5. An electron discharge device having a plate electrode, a chemical clean-up agent applied to one part of said plate, and a flash material applied to a different part of said plate.

In testimony whereof I have hereunto set my hand on this 7th day of March A. D., 1930.
